UNITED STATES PATENT OFFICE.

GRANVILLE A. HUMASON, OF SHREVEPORT, LOUISIANA, ASSIGNOR, BY DIRECT AND MESNE ASSIGNMENTS, TO HUMASON RAIL JOINT COMPANY, OF SHREVEPORT, LOUISIANA, A CORPORATION OF LOUISIANA.

RAIL-JOINT.

1,028,729.

Specification of Letters Patent.

Patented June 4, 1912.

Application filed August 21, 1911. Serial No. 645,105.

To all whom it may concern:

Be it known that I, GRANVILLE A. HUMASON, a citizen of the United States, residing at Shreveport, in the parish of Caddo and 5 State of Louisiana, have invented certain new and useful Improvements in Rail-Joints; and I do hereby declare the following to be a full, clear, and exact description of the invention, such as will enable others 10 skilled in the art to which it appertains to make and use the same.

My present invention relates to improvements in rail joints, and the object of the invention is to stiffen and strengthen the 15 joints of the rails, and yet permit of longitudinal expansion and contraction. In addition to these advantages, the construction of the rail will in a large measure prevent the hammering or pounding of the car 20 wheels as they pass from the end of one rail to the adjacent end of the next rail, and also in a large measure prevent the denting in of the ties, or injury to the chairs from excessive vibration. Furthermore, the tendency 25 of the end of one rail to sag down when the wheel passes over it, causing the adjoining rail to strike the moving wheel, is in a large measure obviated, thus preventing the creeping 30 of the track. These and other advantages in the herein described construction will be understood by reference to the accompanying drawings, in which the same parts are indicated by the same letters throughout the several views.

Figure 1 shows a side elevation of the rail with the fish plates applied, showing one form of the device. Figs. 2 and 3 are details showing the abutting ends of the two rails forming the joint shown in Fig. 1. Fig. 4 shows one of the fish plates. Fig. 5 shows another of the fish plates. Fig. 6 shows a section along the line 6—6 of Fig. 1, and looking in the direction of the arrows, and Fig. 7 shows a modified form of rail joint.

In Figs. 1 to 6, Λ and Λ' represent two abutting rails, whose webs are cut away in an elliptical form, as at a , and also provided with the usual holes a^o for the bolts B passing through the angle plates C and 45 C'. The base of the rail Λ is preferably cut away to form a tongue a' , with shoulders a^2 , registering with the recess a^3 and shoulders a^4 , respectively, on the adjacent rail. Moreover, the web of the rail Λ may be cut

away, as at a^5 , to register with the curved 55 tongue a^6 of the rail Λ' . Thus the ends of the two rails interlock at the base, and the curved portion a^5 serves to resist vertical pressure, while the construction prevents lateral displacement, and therefore strengthens 60 the rail at the joint against the accidents due to excess of lateral pressure. The two angle plates C and C', shown on a smaller scale in Figs. 4 and 5, are provided the one with an elliptical lug c, projecting through 65 the elliptical slot a^7 (see Figs. 1 and 7) in the web of the adjoining rails, and engaging in the elliptical recess c' in the angle plate C'. By having this tongue c made integral with the fish plate C, great strength and rigidity are secured, and by having the socket c' extend only partly through the wall of the fish plate C', the vertical strength of 70 said fish plate is less impaired than if the tongue passed clear on through. The two 75 members are held in engagement by the bolts B in the usual way. The elliptical tongue is provided with a slight clearance at each end with regard to the rails, so that they may expand and contract freely; but at 80 the same time, the flat top and bottom surfaces of the ellipse may transmit the down thrust of the rail joint, and cause the end of one rail to support the other, and also cause 85 the two fish plates to add great vertical strength to the joint. It is preferred to have the fish plates in the form of angle irons, but any ordinary shape of fish plate may be adopted, if desired, and moreover 90 any suitable form of chair may be added, if desired, but this is not a part of my invention, and is not shown herein.

In Fig. 7, the two rails are shown as abutting vertically in the usual way, without the interlocking feature shown in Figs. 1, 2, and 95 3. It will be evident that the fish plates or angle plates shown in Figs. 4 and 5, and hereinbefore described, may be applied as well to a rail joint of this description as to a joint of the description shown in Fig. 1. 100

Having thus described my invention, what I claim and desire to secure by Letters Patent of the United States is:—

1. The combination with two rails having their webs provided each with a semi-elliptical slot adapted to form an elliptical opening when the two rails are abutting, and each provided with bolt holes, of a pair of 105

fish plates, the one provided with an elliptical tongue integral therewith, and the other provided with an elliptical recess adapted to receive said tongue, the said tongue fitting in said elliptical opening in the webs of said rails, and being provided with a slight clearance at either end, with bolts passing through said openings and holding said fish plates against said rail, and holding the end of said elliptical tongue in said elliptical recess in said fish plate, substantially as described.

2. The combination with two rails having their webs provided each with a semi-elliptical slot adapted to form an elliptical opening when the two rails are abutting, and each provided with bolt holes, of a pair of fish plates, the one provided with an elliptical tongue integral therewith, and the other provided with an elliptical recess adapted to receive said tongue, the said tongue fitting in said elliptical opening in the webs of said rails, and being provided with a slight clearance at either end, with bolts passing through said openings and holding said fish plates against said rail, and holding the end of said elliptical tongue in said elliptical recess in said fish plate, the web of one of said rails being cut away as at a^5 , and shouldered as at a^2 , and provided with a tongue a' , and the web of the other rail being cut away as at a^6 to register with said cut away portion a^5 of the first rail, and being provided with a recess to receive said tongue a' , whereby an interlocking joint is secured, which will both assist in securing vertical rigidity and also in preventing lateral displacement, substantially as described.

3. The combination with two rails having

their webs provided each with a semi-elliptical slot adapted to form an elliptical opening when the two rails are abutting, and each provided with bolt holes, of a pair of fish plates, the one provided with an elliptical tongue integral therewith, and the other provided with an elliptical recess adapted to receive said tongue, the said tongue fitting in said elliptical opening in the webs of said rails, and being provided with a slight clearance at either end, with bolts passing through said openings and holding said fish plates against said rail, and holding the end of said elliptical tongue in said elliptical recess in said fish plate, the web of one of said rails being cut away as at a^5 , and shouldered as at a^2 , and provided with a tongue a' , and the web of the other rail being cut away as at a^6 to register with said cut away portion a^5 of the first rail, and being provided with a recess to receive said tongue a' , whereby an interlocking joint is secured, which will both assist in securing vertical rigidity and also in preventing lateral displacement, substantially as described.

In testimony whereof, I affix my signature, in presence of two witnesses.

GRANVILLE A. HUMASON.
